UNITED STATES PATENT OFFICE.

AXEL F. SALSTROM, OF PAXTON, ILLINOIS.

PICTURE-MOLDING FASTENER.

SPECIFICATION forming part of Letters Patent No. 740,046, dated September 29, 1903.

Application filed November 18, 1902. Serial No. 131,894. (No model.)

To all whom it may concern:

Be it known that I, AXEL F. SALSTROM, a citizen of the United States, residing at Paxton, in the county of Ford and State of Illinois, have invented a new and useful Picture-Molding Fastener, of which the following is a specification.

The invention relates to improvements in picture-molding fasteners.

10 The object of the present invention is to improve the construction of picture-molding fasteners and to provide a simple, inexpensive, and efficient device of great strength and durability adapted to be readily applied to picture-moldings and capable of enabling the same to be quickly applied to and removed from walls without injuring the same.

15 The invention consists in the construction and novel combination and arrangement of parts hereinafter fully described, illustrated in the accompanying drawings, and pointed out in the claims hereto appended.

20 In the drawings, Figure 1 is a vertical sectional view of a picture-molding fastener constructed in accordance with this invention and shown applied to a piece of molding. Fig. 2 is an enlarged perspective view of the fastener detached. Fig. 3 is a similar view illustrating a modification of the invention in which the fastener is secured to the molding by tacks. Fig. 4 is a perspective view of another modification of the molding-fastener in which tongues are employed for securing the same to the molding. Fig. 5 is a 25 similar view of another form of the invention in which a tack and tongues are employed for securing it to the molding. Fig. 6 is a perspective view of a molding-fastener constructed of wire and having integral arms.

30 Fig. 7 is a vertical sectional view of another form of molding-fastener constructed of wire and having horizontal bracing-arms constructed of a separate piece of material. Fig. 8 is a perspective view of the form of fastener illustrated in Fig. 7. Fig. 9 is a detail perspective view illustrating a modification of the invention in which the exteriorly-accessible eye is located at the top of the molding at the back thereof. Fig. 10 is a trans- 35

Like numerals of reference designate corresponding parts in all the figures of the drawings.

1 designates a molding-fastener constructed of a single piece of sheet metal or other suitable material and consisting of a vertical body portion 2, extending above the molding 3 and provided with an opening 4, and the said body portion is provided at its bottom with depending vertical supporting-arms 5 55 and an outwardly-extending horizontal bracing-arm 6. The bracing-arm 6 is preferably formed by cutting the blank or plate from which the fastener is constructed upward from the bottom at opposite sides of the center and then bending the partially-severed intermediate portion outward to form the arm 6. The depending supporting-arms 5 fit against the rear face of the molding and are secured to the same by angularly-disposed 60 tongues 7, which are tapered, as clearly shown in Fig. 2, and which are embedded in the back of the molding, as illustrated in Fig. 1. The horizontal arm 6 extends forward over the top of the molding and is provided with a perforation 8 for the reception of a tack 9 or other suitable fastening device, which is driven into the top of the molding. The molding-fastener is hung upon a suitable fastening device 10, such as a nail or screw, 65 which is received within the opening 4, as indicated in Fig. 1, and this fastening device is located above the molding to afford ready access to it, and the picture-molding fastener is adapted to be readily hung on the fastening device 10, and it may be quickly removed therefrom without injuring the wall. As the picture-molding is elevated, the fastener 1 70 will be practically concealed from view, and in practice it will be constructed of a size to 75 accomplish this end.

80 In Fig. 3 of the drawings is illustrated a picture-molding fastener constructed substantially the same as that shown in Fig. 2, with the exception of the depending supporting-arms 11, which are provided with perforations 12 for the reception of tacks or other suitable fastening devices for securing the supporting-arms to the back of the molding. The horizontal bracing-arm 13 is also pro- 85 90 95 100

vided with a perforation 14 for the reception of a tack or other fastening device for securing it to the top of the molding.

In the form of picture-molding fastener 5 illustrated in Fig. 4 of the drawings the arms 15 and 16 are tapered and are provided at their ends with lips or tongues 17 and 18, which are embedded in the top and back of the molding. The depending supporting- 10 arms 19 (shown in Fig. 5) are tapered and provided with tongues 20, and the horizontal arm 21 is constructed much shorter than the horizontal arms of the previous forms to enable it to be connected with the molding adjacent to the rear face thereof.

The picture-molding fastener illustrated in Fig. 6 is constructed of a single piece of wire which is bent to form the upper body portion 22, and the ends of the wire are bent at 20 right angles to form the arms 23 and 24, which terminate in tongues or spurs 25 and 26. These tongues are adapted to be embedded in the top and back of the molding. In Figs. 7 and 8 the molding-fastener is constructed 25 of two pieces of wire, one piece being bent into approximately V shape to form the upper body portion and the depending supporting-arms 28, and the other piece being bent into approximately rectangular form to provide a transverse connecting portion 29 and 30 bracing-arms 30. All of the arms terminate in spurs or tongues adapted to be embedded in the molding. The sides of the body portion are provided with bends 31 to receive 35 the transverse portion of the other piece of wire.

In Figs. 9 and 10 of the drawings is illustrated a modification of the invention, wherein the exteriorly-accessible eye for the reception 40 of the fastening device for securing the molding to a wall is arranged at the top of the molding at the back thereof. This fastener, which may be constructed of any suitable material, such as wire or sheet metal, is 45 shown in Figs. 9 and 10 made of a single piece of sheet metal and provided with arms 32 and 33. The arms 32, which extend over the top of the molding, are bent downward or inward to embrace the same; but they may be embedded 50 in the top of the molding, as indicated in Fig. 7, and the depending arms, which are arranged at the back of the molding, may be secured to the same by tacks, or they may be provided with inwardly-extending tongues 55 or spurs adapted to be embedded in the molding. The arms, which are arranged approximately at right angles to each other, are connected at the angle by a transverse body portion 34, which is offset from the molding to 60 form an exteriorly-accessible eye, the molding being preferably recessed or cut away beneath the angle to expose the eye more fully. The inner edges of the upper bracing-arms and the lower depending supporting-arms 65 preferably diverge, as shown in Fig. 9; but they may be made of any other de-

sired configuration. The form of picture-molding fastener last described may be constructed of several pieces instead of a single piece of metal, as illustrated in the drawings. 70

It will be seen that the picture-molding fastener is exceedingly simple and inexpensive in construction, that it possesses great strength and durability, and that it will enable picture-molding to be readily applied to 75 and removed from the walls without injuring the latter.

It will be understood that various changes in the form, proportion, size, and minor details of construction within the scope of the 80 appended claims may be resorted to without departing from the spirit or sacrificing any of the advantages of this invention.

It will be observed that by the constructions shown in Figs. 4, 6, 7, and 8 of the drawings the downwardly-extending arms, as well as the forwardly-extending arms, of the device will be provided with integral prongs, barbs, or sharpened flanges adapted to be embedded in the wood of the molding, which 90 is thereby firmly connected with the fastening. It will also be observed that these prongs or sharpened flanges are integral with the said arms and, furthermore, that they are so disposed that when driven into or otherwise connected with the top and back of the molding the prongs or flanges of the downwardly and the forwardly extending arms will be disposed practically at right angles to each other, thus forming an extremely firm 100 and at the same time a very simple means of connection. Now it will be observed that in order to effect this connection it is of prime importance that the downwardly and the forwardly projecting arms be possessed of some 105 degree of resiliency or flexibility with relation to each other. By the usual method of application the prongs or sharpened flanges at the lower ends of the downwardly-extending arms will be first driven into the back of 110 the molding, but at the same time it is necessary in order to insure the proper connection that the top of the molding should lie in contact with the under side of the forwardly-extending arm or arms. Unless this were the 115 case the point of the prong or barb would be in contact with the upper edge of the molding while the barbs at the lower ends of the downward-extending arms were driven. The subsequent driving of the barbs at the front 120 ends of the horizontal arms could not then be satisfactorily effected.

In each of the constructions shown in the figures to which reference has been made the material of which the device is constructed 125 is resilient, and the pronged or barbed arms may thus properly be described as possessing flexibility with relation to each other. By the construction specially indicated in Figs. 7 and 8 the natural flexibility of the material 130 is not wholly relied upon, but the forwardly-extending barbed arms are connected hing-

edly with the body having the downwardly-extending barbed arms, so that a positively-flexible connection or hinge connection is effected.

5 What is claimed is—

1. A picture-molding fastener comprising a body portion having forwardly-extending and downwardly-extending arms provided with integral means to engage, respectively, the top and the back of the molding, said arms being possessed of flexibility with relation to each other and to the body of the device.

2. A picture-molding fastener comprising a body portion having forwardly-extending and downwardly-extending arms provided with integral means to engage, respectively, the top and the back of the molding, said arms being hingedly connected with each other.

3. A picture-molding fastener having flexibility-related means integral therewith for engaging and firmly connecting said fastener with the top and with the back of a picture-molding.

4. A picture-molding fastener comprising a body having forwardly-extending and downwardly-extending arms, and means whereby the said arms may be connected securely with the top and with the back of a molding.

In testimony that I claim the foregoing as my own I have hereto affixed my signature in the presence of two witnesses.

AXEL F. SALSTROM.
